ATTACHMENT FOR SEWING MACHINES

Alexander Soltan, Elmhurst, N. Y., assignor to
Percy W. Valentine, Brooklyn, N. Y.

Application September 1, 1938, Serial No. 227,957

10 Claims. (Cl. 112—62)

This invention relates to attachments for sewing machines and particularly machines employed for sewing the soles of shoes to the uppers, and the object of the invention is to provide an attachment of the class described having a work-piece support capable of yieldable movement with respect to the work-piece to compensate for irregularities that may prevail therein and also a support of this kind capable of a lateral swinging as well as circumferential swinging movement with respect to a companion work-piece support to give free access to the attachment in assembling the work-piece therein; a further object being to provide a work-piece support in the form of a spreader for engaging the flange portion of a work-piece with means on the surface of the spreader supporting the work-piece to provide free passage of the needle of the machine through the work-piece at the outer surface of the spreader; a further object being to provide means for manually moving the first named hook-shaped work-piece support away from the work-piece in coupling and uncoupling the work-piece with the attachment and against the action of the tensile means moving said support into engagement with the workpiece, and with these and other objects in view the invention consists in an attachment of the class and for the purpose specified which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a perspective view illustrating the general arrangement of the attachment when in operative position, with part of the construction diagrammatically shown in extended position in dotted lines.

Fig. 2 is a section substantially on the line 2—2 of Fig. 1.

Fig. 3 is a section substantially on the line 3—3 of Fig. 1.

Fig. 4 is a partial section on the line 4—4 of Fig. 1.

Fig. 5 is a bottom plan view of a part of the structure shown in Fig. 1.

Fig. 6 is a side edge view of the device as seen in Fig. 5, and

Fig. 7 is a sectional detail view somewhat similar to Fig. 2 and showing a modified form of construction.

The attachment forming the subject matter of the present invention forms a continuation in part of the structure disclosed in my prior application, Serial No. 139,486 filed April 28, 1937, having since issued in Patent #2,134,010. Generally speaking, the present attachment incorporates additional structural features rendering the attachment more suitable and adaptable for use in performing the desired function, namely, in stitching a sole having an integral welt, to the upper.

In Figs. 1 to 4 inclusive, I have shown one adaptation of the invention, and in Fig. 1, 10 represents a supporting bracket or base having a lower L-shaped portion 11 fashioned to mount the same in connection with a sewing machine of the type and kind under consideration so as to arrange the attachment properly with respect to the needle of the machine. At 12 is shown a bracket which is U-shaped in cross-sectional form, and inner adjacent surfaces of the side walls thereof are provided with lateral projections which fit in grooves 13 in a block or bar 14, whereby said bar may be adjusted forwardly and backwardly in the bracket. A bolt 15 is employed for securing the bar 14 in different positions of adjustment by drawing the side walls of the U-shaped portion 12 of the bracket firmly upon said block or bar.

A supplemental block 16 is adjustably supported on the rear reduced end 17 of the block 14 and consists of a bottom plate 18 having an upwardly extending bearing portion 19 for receiving a rocker shaft 20. One side of the bottom plate 18 is provided with a downwardly extending flange 21 in which is supported adjustment screws 22 which operate in connection with the reduced end 17 of the block 14 in supporting the supplemental block 16 in proper alignment on the block 14, which will be apparent. A screw 23 passes through the extension 17 and is coupled with the plate 18 in securing the supplemental block 16 in position. This screw serves to draw the plate 18 downwardly upon four seating screws 24 of the socket type which will control the vertical adjustment of the supplemental block 16 in the block 14, as will be apparent. The screws 22 adjust the plate 18 laterally, whereas the screw 23 serves to retain the plate 18 in different positions of adjustment.

These latter features are common in the Patent #2,134,010 heretofore referred to, but are repeated simply to make the present illustration understandable with respect to the several adjustments which are attributed to one of the work-

piece supporting parts; for example, the work-piece supporting part 25 which is yoke-shaped and hook-shaped in form, that is to say, is provided with an upwardly extending yoke-shaped portion 26 and a laterally extending hook-shaped arm portion 27 having a rounded end 28 for engaging the work-piece 29, as seen in Fig. 4 of the drawing. The work-piece 29 is in the form of a sole including an integral welt or welt lip as at 30. It will 10 be understood that in this figure, the upper to which the welt is attached, is not shown, only for the purpose of simplifying the illustration.

The support 25 also includes an enlarged portion 31 which is substantially L-shaped in form 15 and includes a rearwardly extending rod 32 which passes through a bearing 33 in a swinging and tiltable arm 34. The arm is arranged to swing laterally upon a screw pin 35 having a knurled head 36, said head operating upon a conical spring 37 which provides slight raising movement of the 20 arm including the member 25 with respect to a supporting plate 38 which is integral with the inner end of the rocker shaft 20 and extending laterally to one side thereof as is illustrated in Fig. 1 25 of the drawing.

The plate 38 has a forwardly directed extension 39 upon which the arm 34 as well as the enlargement 31 of the member 25 seats. The extension 39 has an upwardly projecting pin 40 adapted to enter an aperture 41 in the arm 34 for keying the arm against displacement from the swinging plate 38 or the extension 39 thereof. However, by raising the arm against the action of the spring 37, the arm may be swung on the screw pin 35 laterally, and said arm including the member 25 may also be swung on the rocker shaft 20 upwardly substantially in the manner illustrated in dotted lines in Fig. 1 of the drawing. This swinging movement of the member 25 is provided for giving 40 free access to the attachment in mounting a work-piece therein or in removing the work-piece from the attachment. The member 25 or the rounded end 28 thereof may be adjusted toward and from the work-piece by the adjustment of the shaft 20 45 controlled by the nuts 42 arranged upon the shaft 20, one of which includes an enlarged collar 43 operating in a recess 44 in the plate 18 so that the shaft may be drawn forwardly and backwardly in the bearing 19 to provide the desired adjustment, 50 and the other of which constitutes a lock nut. The plate 38 extends rearwardly and forms the support for the screw pin 35 as will be apparent, and also serves to support the rear end of the arm 34.

Pivoted to the rear end of the arm as seen at 55 45 is an operating lever 46 which is also pivoted as seen at 47 to a block 48 on the rear squared or flattened end of the rod 32 as clearly seen in Fig. 2 of the drawing. The block 48 is adjustably 60 secured at different positions longitudinally of the squared or flattened end of the rod 32 so as to adjust the tension of a coil spring 49 arranged upon the rod between said block and the bearing portion 33 of the arm 34 so as to regulate tensional 65 engagement of the workpiece supporting member 25 and the end 28 thereof upon the work-piece, while at the same time permitting free movement of the work-piece with respect to the member in the event of any slight variations that may 70 prevail therein. It will be understood that the member 25 is movable outwardly with respect to the arm 34 against the action of the spring. The finger-grip lever 46 provides for manual movement of the member 25 into a disengaging position 75 in the operation of detaching the work-piece

and in swinging the member into raised position.

Arranged upon the top of the block 14 is a plate 50, supporting at its forward end a projecting rounded stop 51. Adjacent the stop 51, the block 14 is provided with an undercut projecting flange 52, at one side of which is a welt supporting element 53 normally depressed by a spring 54 as in the construction shown in said prior Patent #2,134,010. The element 53 serves to retain the welt 30 in position upon a 10 spreader 55 and the rounded supporting surface 28 of the member 25 and yieldably holds the work-piece in proper position as will appear upon a consideration of Fig. 4 of the drawing. The spreader 55 is arranged upon one end of a 15 stub shaft 56 adjustably secured in the block 14 by means of a set screw 57, so that the position of the spreader with respect to the undercut 52 may be regulated. The outer surface of the spreader 55 is also cut rearwardly to give free access to the needle of the machine, and at one side of the surface is an outwardly projecting supplemental spreader 55a which serves to support the sole 29 away from the outer surface of the spreader 55 to provide free action of the needle in the stitching operation of the machine, as will be apparent.

In Fig. 7 of the drawing I have shown a slight modification wherein means is shown for operating the arm 34a through a foot treadle on a 30 machine which actuates an operating rod 58 coupled with a projecting end 59 on the arm 34a as seen at 60, the arm being pivoted to the supporting plate 38a as seen at 61. With this construction the lateral swinging movement of the 35 arm will be dispensed with, but otherwise the arm will be of the same general structure as that shown in Figs. 1 to 6 inclusive. A pin 62 is passed through the rear end portion of the arm and is threaded to receive an adjustable nut 63 to regulate the tension of a spring 64 against which the arm 34a will be raised.

It will of course be understood that the member 25 will have the same movement in the arm as shown in Figs. 1 and 2 of the drawing, but 45 the member including the means for actuating the same is omitted in Fig. 7. In this connection it will be understood that my invention is not necessarily limited to any particular manner of actuating or adjusting the several work-piece supporting members or elements, provided the relative 50 adjustments and movements heretofore indicated can be accomplished.

From the foregoing, it will appear that in addition to the two way adjustment provided between the block 17 and the supplemental block 16 by the screws 22, 23, and 24, the supporting plate 38 for the arm 34 swinging about the axis 20 is also adjustable longitudinally of the attachment in the bearing 19. The member 25 including 60 its supporting arm 34 may either be swung laterally or vertically as in Fig. 1, and said member is resiliently supported in operative position and capable of longitudinal movement in its support. The spreader 55 is also adjustable with respect 65 to the member 25 and the undercut 52 to adapt the attachment to work-pieces of various sizes and having different forms and sizes of welts, and the support 53 serves to yieldably maintain the work-piece in operative position. In other words, 70 my improved attachment might be said to be universally adjustable and adaptable to various work-pieces and also readily accessible for the insertion and removal of work-pieces whenever desired, accomplishing the latter result quickly and 75

without disturbing any adjustments previously made.

In some instances it may be desirable to change the contour of the member 25 or the yoke or hook-5 arm portions thereof when operating upon different work-pieces, but this may be done by simply substituting one member for another in the attachment and without disturbing the rest of the mechanism thereof. This would also apply to the 10 spreader 55.

The support 53 in addition to engaging the sole and welt, also supports that part of the upper to be secured thereto so as to support both work-pieces in firm engagement with each other in the 15 stitching operation.

Having fully described my invention, what I claim as new and desire to secure by Letters Patent, is:

1. An attachment for use in supporting the sole 20 and upper in the operation of stitching the same together, said attachment comprising a spreader forming one work-piece support, a combination hook-shaped and yoke-shaped member forming another work-piece support cooperating with said 25 spreader, a swinging plate for supporting said member, means for adjusting the position of said plate to properly position said member with respect to the spreader, an arm swingably supported on said plate and with which said member is 30 coupled, and means keying the arm to the plate in retaining said member in operative position.

2. An attachment for use in supporting the sole and upper in the operation of stitching the same together, said attachment comprising a 35 spreader forming one work-piece support, a combination hook-shaped and yoke-shaped member forming another work-piece support cooperating with said spreader, a swinging plate for supporting said member, means for adjusting the 40 position of said plate to properly position said member with respect to the spreader, an arm swingably supported on said plate and with which said member is coupled, means keying the arm to the plate in retaining said member in operative position, and means for yieldably supporting 45 said member in the arm to provide automatic movement of the arm relatively to said spreader.

3. An attachment for use in supporting the sole and upper in the operation of stitching the same 50 together, said attachment comprising a spreader forming one work-piece support, a combination hook-shaped and yoke-shaped member forming another work-piece support cooperating with said spreader, a swinging plate for supporting said 55 member, means for adjusting the position of said plate to properly position said member with respect to the spreader, an arm swingably supported on said plate and with which said member is coupled, means keying the arm to the plate in retaining said member in operative position, means for yieldably supporting said member in the arm to provide automatic movement of the arm relatively to said spreader, and manual operating 60 means cooperating with the last named means to manually move the member with respect to said arm.

4. In an attachment for supporting the sole and upper in the operation of stitching the same 65 together, a spreader to engage and support the welt lip of the sole in the stitching operation and the surface of the spreader having a supplemental spreading element for spacing the welt lip from the sole to provide needle clearance in the stitching operation, and other movably sup- 70

ported means adjacent the spreader for engaging and supporting the work-piece thereon.

5. In an attachment for supporting the sole and upper in the operation of stitching the same together, a spreader to engage and support the 5 welt lip of the sole in the stitching operation and the surface of the spreader having a supplemental spreading element for spacing the welt lip from the sole to provide needle clearance in the stitching operation, other movably supported means 10 adjacent the spreader for engaging and supporting the work-piece thereon, one of said last named means comprising a hook-shaped member swingably supported with respect to the spreader, and means yieldably supporting said member to move 15 toward and from the spreader in a direction of the outer surface thereof.

6. In a sewing machine attachment of the class described, in combination with a stationary work-piece support, a work-piece supporting member 20 cooperating with the first named support in retaining the work-piece in position during the stitching operation thereof, means for swinging said member in two directions with respect to the stationary support and for adjusting a part of 25 said member for alinement and spacing with the stationary support, and means for yieldably supporting said member to move toward and from the stationary support.

7. An attachment for sewing machines of the 30 class described for supporting the sole and upper in the operation of stitching the same, said attachment comprising a spreader for engaging the welt lip of the sole, means for retaining the upper upon the sole and said welt lip, an arm mounted to swing vertically on a horizontal axis, a work-piece supporting member slidably engaging said arm and having a hook-shaped portion terminating at its free end adjacent said first named means, and means yieldably supporting said member in said arm to provide movement of said end of the hook-shaped portion thereof toward and from said first named means in supporting a workpiece therebetween. 35

8. An attachment for sewing machines of the 40 class described for supporting the sole and upper in the operation of stitching the same, said attachment comprising a spreader for engaging the welt lip of the sole, means for retaining the upper upon the sole and said welt lip, an arm mounted to swing vertically on a horizontal axis, a workpiece supporting member slidably engaging said arm and having a hook-shaped portion terminating at its free end adjacent said first named means, means yieldably supporting said member in said arm to provide movement of said end of the hook-shaped portion thereof toward and from said first named means in supporting a workpiece therebetween, means 45 detachably coupling said member with said arm, and means forming a yielding pivot between said member and arm to provide for manual disengagement of said last named means and independent swinging movement of the member with respect to said arm. 50

9. In an attachment of the class described having a spreader for engaging the welt lip of a sole in the operation of stitching the sole and upper together, a workpiece supporting member having a hook-shaped part, the free end 55 of which is disposed adjacent said spreader, means supporting said member to adjust the end of said part toward and from the spreader and to swing said member vertically about the axis of the spreader, other means yieldably sup- 60

porting said part to tensionally move the end thereof in the direction of the spreader in supporting a workpiece on said spreader, and other means yieldably coupling said member with the 5 first named means to provide vertical and lateral swinging movements of said member with respect to said first named means.

10. In an attachment of the class described having a spreader for engaging the welt lip of a 10 sole in the operation of stitching the sole and upper together, a workpiece supporting member having a hook-shaped part, the free end of which is disposed adjacent said spreader, means supporting said member to adjust the end of said

part toward and from the spreader and to swing said member vertically about the axis of the spreader, other means yieldably supporting said part to tensionally move the end thereof in the direction of the spreader in supporting a workpiece on said spreader, other means yieldably coupling said member with the first named means to provide vertical and lateral swinging movements of said member with respect to said first named means, and a finger piece coupled with 10 said part to move the end thereof in a direction away from said spreader in the insertion and removal of the workpiece.

ALEXANDER SOLTAN.
